UNITED STATES PATENT OFFICE.

ANDREW KOZAK, OF LILLY, PENNSYLVANIA.

WATER AND CARBIDE CAN.

Application filed May 25, 1926. Serial No. 111,604.

This invention relates to certain new and useful improvements in a combined carbide can and water receptacle and combines in a single device a receptacle divided into separate compartments with independent filling openings for carbide and water and being designed for use by miners, it is intended that the same be constructed of a size to be conveniently carried in a pocket so that an additional supply of carbide and water for a carbide lamp will always be accessible.

A further object of the invention is to provide a device of the type above set forth wherein the container embodies a partition wall with a filling opening at each end of the container for the carbide and water and with a water nozzle supported in the side wall of the container and partition wall in a manner to permit complete drainage of the water receptacle when the container is inverted.

With the above and other objects in view that will become apparent as the nature of the invention is better understood, that same consists of the novel form, combination and arrangement of parts hereinafter more fully described, shown in the accompanying drawings and claimed.

In the drawing, wherein like reference characters designate corresponding parts throughout the several views,

Figure 1 is a side elevational view of a combined carbide can and water receptacle constructed in accordance with the present invention, and

Figure 2 is a vertical cross-sectional view showing the partition dividing the container into carbide and water carrying compartments with the end closure plug for each compartment and the water spout in communication with the water compartment.

The carbide can and water receptacle, being intended for use by miners in the charging with carbide and water of a carbide lamp, is constructed of a size to be conveniently carried in the pocket and is of the general configuration illustrated in Figure 1, the device comprising a container having a side wall 1 of barrel formation that is slightly larger at its lower or base end than at the upper end thereof. The container is circular in cross-section and intermediate the upper and lower ends thereof at a point adjacent to and above the transverse median line is provided with a partition wall 2 dividing the container into an upper compartment to receive carbide C and a lower compartment to receive water W.

The upper end of the container is provided with a filling opening for the introduction of the carbide C and said opening is surrounded by an internally threaded annular neck 3 that is closed by a threaded disk stopper 4. The lower or base end of the container is provided with a filling opening for water W and said opening is surrounded by an inwardly directed internally threaded annular flange 5 that receives the externally threaded annular flange 6 upon the disk stopper 7. A gasket 8 is interposed between the peripheral edge of the disk stopper 7 and the open end of the water compartment to form a water tight connection.

To facilitate removal of the water from the water compartment for delivering water to a carbide lamp, there is provided a spout 9 passing through the side wall 1 of the container and the carbide receptacle with the inner end of the spout passing through the partition wall 2 and terminating in proximity thereto and also having one side thereof juxtaposed to the side wall of the container at 9^a as shown in Fig. 2. The outer end of the nozzle 9 receives a closure cap 10. By so locating the inner end 9^a of the nozzle 9 with respect to the side wall 1 of the container, it will be possible to completely drain the water compartment and effect use of the entire contents thereof. As shown in Fig. 2, the outer side of the inner end of the spout is juxtaposed to the side wall 1 of the container so that in tilting the container, all water may be drained from the water compartment. The end stopper 7 forms a water tight closure for water receptacle while the filling openings for the water and carbide are at opposite ends of the can.

While there is herein shown and described the preferred embodiment of the present invention, it is nevertheless to be understood that minor changes may be made therein without departing from the spirit and scope of the invention as claimed.

What is claimed as new is:—

In a combined carbide can and water receptacle, a container of cylindrical formation tapering toward each end, a cross-partition intermediate the ends thereof dividing the same into an upper carbide can and a lower water receptacle, the opposite ends of the container having filling openings, a disk stopper threaded into each opening, a water tight connection between the disk stopper and water receptacle, with the peripheral

edge of the last named stopper extending outwardly of the side wall of the receptacle and forming a base seat for the receptacle, and a pouring spout supported by the side wall 5 of the container and partition wall with its major length disposed inwardly of the carbide receptacle and with the outlet end of the spout terminating adjacent the filling opening for the carbide can and exteriorly 10 thereof, that part of the spout within the

carbide can lying juxtaposed to the side wall of the can, and the outer side of the inner end of the spout contacting the adjacent side wall of the water receptacle adjacent the lower face of the partition whereby the entire contents of the water receptacle may be drawn through the spout. 15

In testimony whereof I affix my signature.

ANDREW KOZAK.
